Primary Examiner — Holly E Thurman*Assistant Examiner* — Ieisha N Price(74) *Attorney, Agent, or Firm* — Stetina Brunda Garred
and Brucker(57) **CLAIM**

The ornamental design for a handle mount, as shown and described.

DESCRIPTION

FIG. 1 is an environmental top front perspective view of the handle mount of the present invention showing our new design;

FIG. 2 is a top front perspective view thereof;

FIG. 3 is a bottom front perspective view thereof;

FIG. 4 is a top plan view thereof;

FIG. 5 is a front elevational view thereof;

FIG. 6 is a bottom plan view thereof;

FIG. 7 is a rear elevational view thereof; and,

FIG. 8 is a left side elevational view thereof.

The dotted lines in the figures depict environmental structure
and form no part of the claimed design.**1 Claim, 3 Drawing Sheets**(56)
